ELECTRICAL IMPULSE SENDING DEVICE

Gerald Deakin, New York, N. Y., assignor to International Standard Electric Corporation, New York, N. Y., a corporation of Delaware

Original application February 24, 1944, Serial No. 523,626, now Patent No. 2,406,001, dated August 20, 1946. Divided and this application March 19, 1945, Serial No. 583,478

11 Claims. (Cl. 177—380)

1 This invention relates to new and useful improvements in electrical signalling and switching systems and more particularly to improved impulse sending devices for use in telecommunication switching systems such as automatic and semi-automatic telephone exchanges.

An object of the invention is to increase the speed and reliability with which control impulses may be transmitted from a first point to a second point, for example, from a substation or the like to a control exchange or other position where selecting equipment is located.

With this object in view, I have provided in my copending application No. 523,626, filed February 24, 1944, now U. S. Patent No. 2,406,001, granted August 20, 1946, of which this application is a division an arrangement in which upon the extension of a line to a distant point at which a selective control is to be exercised, a source of alternating current is coupled to the line. A signalling device, such as a dial, is then actuated to periodically reverse the polarity of a uni-directional current conducting device, such as a dry contact rectifier, in the line circuit. At the distant point there is connected to the line circuit polarized relay means which responds to the reversals of polarity of the current flow and controls switching apparatus therewith.

The pulse cycle of the standard interrupter dial circuit at present used in automatic telephone exchange systems consists of a closure and an opening of a single stepping relay direct current circuit with a 60/40 ratio of opening to closure. One digit is recorded per cycle, and the opening of the circuit is the useful part of the cycle; the closure of the circuit represents time unavoidably wasted to prepare the circuit to receive the next pulse. In alternating current rectifier dialing circuits the complete pulse cycle consists of two pulses, a positive pulse and a negative pulse each one useful in recording a digit as well as in assisting the restoration of the relay which is operated by the preceding pulse of opposite polarity. For example, in a preferred arrangement in which two oppositely polarized relays are used for responding to the pulses, these two relays operate on a "push-up, push-back" principle and thus the complete cycle is used by both relays while rectification with polarization places the operation of the two relays 180° out of phase.

The positive and negative pulses consist in fact of trains of positive and negative pulses at the periodicity of the alternating current source, but for all practical purposes these integrated series

of pulses act as though they were pulses of the direct current of the proper polarity.

An object of the present invention is the provision of a simple and effective device for intermittently reversing the polarity of a uni-directional current conducting device in the line circuit, a predetermined and variable number of times.

These and other features and advantages of my invention will be more clearly understood from the following description of a preferred embodiment thereof and the appended claims.

In the accompanying drawings:

Fig. 1 is a circuit diagram of a subscriber set circuit provided with a rectifier dial for use in a system, as described in my copending application referred to, in which a direct current loop is present over the line until dialing commences;

Fig. 2 is a plan view of a rectifier dial showing the finger hole plate and finger stop;

Fig. 3 is an elevation partly in section taken on the line 3—3 of Fig. 2;

Fig. 4 is a section taken on the line 4—4 of Fig. 3.

Fig. 5 is a section taken on the line 5—5 of Fig. 3, and

Fig. 6 shows a detail of the spring nest in the rectifier dial.

Referring first to Fig. 1, the subscriber set circuit shown therein is apart from the rectifier dial of the usual type. The rectifier dial which will be described later in connection with Figs. 2 to 6 includes a rotating rectifier R and a home contact spring nest S. The operation of the rectifier dial from a circuit point of view is as follows: When the finger wheel is moved off normal a pin P3 allows spring B to break contact with spring C which removes a short circuit from the rectifier R, and to make contact with spring A which short circuits the induction coil and transmitter. Pin P1 causes spring F to break contact with spring G until shortly before the first finger hole reaches the finger stop; in other words, the line circuit is momentarily opened each time the finger wheel is turned to the finger stop. When the finger wheel is released the rectifier R makes one-half of a revolution for each finger hole passing the finger stop but before the last finger hole passes the finger stop P1 again opens contact between the springs F and G thereby momentarily opening the line circuit which causes the digit change-over in the register to take place. As will be clear from the subsequent description of the rectifier dial, the rectifier is always returned to its predetermined position of polarity.

Thus, should an odd digit be dialed the rectifier is given a half revolution to restore it to its normal position while contact between springs F and G is open.

From what has been said above it will be seen that when the digit 1 is dialed the initial closure of the line through the rectifier R in its normal position sends the first pulse to record the digit 1 and that when the finger wheel is released, the circuit is opened for the change-over before the rectifier reverses the current.

The sub-station set circuit shown in Fig. 1 is intended for use with a system incorporating registers of the kind shown in my copending application referred to in which a direct current loop is present over the subscriber's line until dialing actually commences. In an alternative method of operation alternating current is applied to the subscriber's line as soon as the register is connected up.

The construction of a suitable rectifier dial is illustrated in Figs. 2 to 6 and will now be described. Referring first particularly to Figs. 3 and 4, the dial consists of two main parts, an upper part 1 housing the home contact nest HO and a lower part 2 housing the rotating rectifier S.

In the upper housing 1 is mounted a finger wheel 3 provided with the usual finger holes and attached to a shaft 4 which rotates in a sleeve 5 in the housing 1 when driven by a coiled spring 6, one end of which is attached to the finger wheel 3, while the other rests in a groove in the housing part 1. A segment 7 is attached to shaft 4 by nut 8. A pawl 9 is pivoted to the segment 7 and tends to engage the teeth of a ratchet wheel 10 under the tension of a spring 10a.

Ratchet wheel 10 and a gear wheel 11 are attached to each other and rotate freely on the lower extension of shaft 4. They are held in position by the flat head 11a of a bearing pin 12 when the lower part 2 housing the rectifier unit is mounted in position. Ratchet wheel 10 has a number of teeth corresponding to the number of positions of the finger wheel 3. Every other tooth is relatively long (in a radial sense). When the finger wheel 3 is in its normal position one edge of the segment 7 rests against a back stop 13 formed in the housing 1 and a raised surface 14 on the inner periphery of the housing 1 adjacent the stop 13 lifts the pawl 9 so that it engages only the deep teeth of a ratchet 10.

When the finger wheel 3 is rotated by the user, the segment 7 moves clockwise and when it has moved an angular distance equal to about one finger hole spacing the raised surface 14 no longer bears on the pawl 9 and the latter rotates slightly about its pivot so as to engage both the long and the short teeth of the ratchet wheel 10. Should the finger wheel be turned a distance equal to five finger holes, that is, should the digit 3 be dialed, since there is a space equal to two finger holes between the hole number 1 and the finger stop 19, the pawl 9 will engage a short tooth. When the finger wheel is released the spring 6 will rotate the ratchet wheel 10 counterclockwise. As the segment 7 approaches its home position, the pawl 9 engages the raised surface 14 and thus disengages the short tooth but reengages the next long tooth just before the segment 7 comes to rest against the back stop 13. The object of this arrangement is to insure that the rectifier S always returns to its predetermined position of polarity.

The home spring next consists of five springs A, B, C, F and G, Fig. 4, mounted in a block of

insulating material 30 fixed to the upper housing 1. Two pins P1 and P3 are mounted on the segment 7 in such position that when the finger wheel is moved off normal, pin P1 opens the contact between springs F and G, whilst pin P3 opens the contact between springs B and C and permits contact to be made between springs A and B. The segment 7 is of insulating material.

Assume now that the digit 1 is dialed. When the finger is placed in hole number 1, Fig. 2, and the finger wheel is moved off normal, pin P1 engages the tip 15 of the extension of spring F, Figs. 4 and 6; and breaks the normal contact between springs F and G. Spring F is cut away at its lower edge and provided with an inclined lip 16. When the hole number 1 has been moved an angular distance less than two finger hole spaces, pin P1 rides over the lip 16, Fig. 4, and disengages the spring F, so that when the finger reaches the finger stop 19 contact between springs F and G is again made. The three home contact springs A, B and C are shown in their normal positions in Fig. 4. When segment 7 is moved off normal pin P3 disengages spring B thereby causing contact to be broken with spring C and made with spring A. The springs A, B and C remain in this position until the dial returns to normal.

When the finger wheel 3 is released, after it has moved about three-quarters of a finger hole space, pin P1 reengages the projecting lip 16 of spring F and again opens the contact between springs F and G. When segment 7 reaches its normal position against the back stop 13, contact between springs F and G is restored.

The lower part 2 houses the rectifier discs S, Figs. 3 and 5. These are assembled on a bushing 21 of insulating material. Brush 20a is clamped against the rectifier disc on one side of the rectifier unit and brush 20b is clamped against the disc on the other side by means of nuts 22. A bearing pin 12 which passes through the bushing 21 has screwed to it a gear wheel 23 and rotates in bushings 24 attached to the upper and lower covers of the rectifier housing 2. The bearing pin 12 is grooved so that when it is slipped through the bore of the bushing 21 the rectifier assembly S and brushes 20a and 20b rotate with the bearing pin 12 and the gear wheel 23.

The upper and lower brushes 20a and 20b rub against collector rings 24a and 24b mounted on the inside wall of the housing 2 as shown in Fig. 5. The external connections are connected to the collector rings 24a and 24b. Gear wheels 11 and 23 are interconnected by pinions 25 which are attached to each other and held in position by a bearing pin 26 mounted in the lower end of the housing portion 2. The ratchet and gear wheels are assembled so that when the wheel 10 is in the position shown in Fig. 4 the rotating rectifier unit S is in the position shown in Fig. 5. The ratio of the various gears is such that the rectifier unit S makes one complete revolution when the finger wheel 3 moves an angular distance equal to two finger hole spaces.

The setting of brushes 20a and 20b, Fig. 5, is such that when they engage the insulating surfaces 27 between the collector rings 24a and 24b as position 2 of the ratchet wheel passes the normal position 1 on the return journey, the pin P1 engages lip 16 of the spring F and opens the contact between springs F and G. Thus the contact between these springs is opened before the brushes 20a and 20b make contact with the succeeding collector rings.

As speed control of a rectifier dial is not critical it is sufficient to weight the brushes 20a and 20b at their ends so that they act both as governor wings as well as collector brushes.

Although the invention has been described with reference to a specific construction of rectifier dial my invention is not to be construed as limited to this construction since many modifications coming within the scope of the appended claims will readily occur to those versed in the art. Moreover as will be appreciated the rectifier dial of my invention is applicable for use in any type of selector system in which the operation of switching apparatus is controlled by trains of impulses.

What is claimed is:

1. A pulsing device for a telecommunication switching system, comprising a uni-directional current conducting element, a pair of contacts for connecting said element in a signalling circuit, means for connecting two output electrodes of said element respectively to said contacts and means between said contacts and said element for rotating said element and said means for connecting with respect to said contacts whereby the polarity of said element with respect to said contacts is intermittently reversed a predetermined and variable number of times.

2. A pulsing device for a telecommunication switching system comprising a rectifier, contacts for connecting said rectifier in an external signalling circuit and means between said contacts and said element for rotating said rectifier with respect to said contacts whereby the direction of polarity of said rectifier with respect to said contacts is reversed a predetermined and variable number of times.

3. A pulsing device for a telecommunication switching system comprising a unidirectional current conducting element, contacts for connecting said rectifier in an external signalling circuit, a rotatable member, means for turning said rotatable member a variable angular distance, and means between said contacts and said element under the control of said rotatable member for rotating said element with respect to said contacts whereby the direction of polarity of said element is reversed with respect to said contacts a predetermined number of times dependent upon the extent of the angular movement of said rotatable member.

4. A pulsing device for a telecommunication switching system comprising a dry contact rectifier, contacts for connecting said rectifier in signalling circuit, a rotatable member, manually operable means for turning said rotatable member a variable angular distance, and a commutator device under the control of said rotatable member for rotating said element with respect to said contacts whereby the direction of polarity of said rectifier is reversed with respect to said contacts a predetermined number of times dependent upon the extent of the angular displacement of said rotatable member.

5. A pulsing device for a telecommunication switching system comprising a uni-directional current conducting device, contacts for connecting said device in a signalling circuit, a first rotatable member, a second rotatable member, means for turning said first rotatable member a variable angular distance from a normal position against the tension of a spring, means for coupling said first rotatable member to said second rotatable member during its return movement to said normal position, and a rotary commuta-

tor device controlled by the rotation of said second rotatable member for reversing the direction of polarity of said uni-directional current conducting device with respect to said contacts a predetermined number of times dependent upon the extent of the angular displacement of said first rotatable member.

5 6. A pulsing device according to claim 5 wherein means is provided for insuring that said commutator device always returns to a rest position in which said uni-directional current conducting device has a predetermined polarity with respect to said contacts.

10 7. A pulsing device for a telecommunication switching system comprising a rotatable finger hole disc, a rotatable ratchet wheel, spring means for returning said disc to a fixed normal position, a pawl for rotating said ratchet wheel during the return movement of said finger hole disc, a rectifier element mounted on a spindle to rotate in bearings, a pair of diametrically arranged brushes mounted on said rectifier element and electrically connected to the two electrodes thereof, a pair of substantially semi-circular segmental contacts adapted to be engaged by said brushes during the rotation of said rectifier element and a mechanical coupling between said ratchet wheel and said spindle.

15 8. A pulsing device according to claim 7 wherein alternate teeth of said ratchet wheel are of increased radial length and means is provided for adjusting the position of said pawl as the said finger hole disc approaches its position of rest so that said pawl always engages a long tooth when the said disc is in its rest position.

20 9. A pulsing device according to claim 7 further comprising a plurality of contact springs, a plate mounted to rotate with said finger disc and a pin mounted on said plate and arranged to actuate said contact springs when said finger disc is moved out of its position of rest.

25 10. A pulsing device for a telecommunication switching system comprising a rotatable finger hole disc, means for turning said disc a variable angular distance from its normal position against the tension of a spring, a rotatable member, means for coupling said disc to said member during the return movement of the disc to its normal position, a dry contact rectifier, contacts for connecting said rectifier in a signalling circuit and means actuated by said rotatable member on the return movement of said disc to reverse the direction of polarity of said rectifier with respect to said contacts a predetermined number of times dependent upon the angular displacement of said disc.

30 11. A pulsing device according to claim 1 in which said pair of contacts for connecting said element in a signalling circuit comprises a pair of essentially semicircular contacts.
